POWER BENDING MACHINE FOR DIES

Stanley Leskiewicz, Lynn, and Frederick A. Hartung, Beverly, Mass., assignors to Stanley Leskiewicz, John Hermanson, and Joseph Toll, copartners, doing business as North Shore Cutting Die Company, Lynn, Mass.

Application April 21, 1949, Serial No. 88,816

7 Claims. (Cl. 153—48)

1

This invention relates to a power bending machine for shaping metal stock, such as used in making shoe dies, paper cutting dies, millinery dies and the like. By way of illustration, in the shoe industry, dies are commonly used for cutting out shoe parts, such as soles, innersoles, uppers, vamps, quarters and the like. These shoe parts are commonly cut by dies of varying size and height, shaped to make the proper cut. So-called clicker dies are ordinarily made from a strip of cold and hot rolled steel from about $\frac{1}{8}$ to $\frac{1}{4}$ inch thick and from $\frac{3}{4}$ inch to $1\frac{1}{2}$ inches high, and these are normally formed on hand operated bending machines which bend the die stock to the desired shape in conformity with a pattern which is provided. So-called handle dies are made from similar stock but are ordinarily higher, and range from $1\frac{1}{2}$ to $2\frac{1}{2}$ inches in height. So-called walker dies, however, for cutting out heavy or thick pieces of leather, rubber and other composition materials, such as are used in making outer soles for shoes, are made from very heavy hot rolled steel from about $\frac{1}{8}$ to $\frac{1}{2}$ inch thick and from 1 inch to 6 inches in height. These heavy walker dies at the present time are made by hand forging, whereby a blacksmith heats the die stock in a forge to red heat and forms the die by bending it over an anvil with a hammer. One such die an hour, and eight a day, is the average production of a skilled operator by the hand forging process.

The hand-operated bending machine for dies is, of course, not strong enough for bending heavy dies such as walker dies, and which in the past have been made from hot rolled steel, as stated. Attempts have been made in the past to develop a power bending machine for forming heavy dies from cold rolled steel, but great difficulty has been experienced in providing the great force and power necessary, and applying it lightly and gently, as it must be applied to bend a metal die for instance into an evenly curved shape. At the same time means must be provided for varying the point at which the force is applied to the die stock being shaped. However, we have succeeded in producing such a machine for power bending heavy dies from cold rolled steel, and it is possible in this machine to shape a walker die, for instance, from cold rolled steel, in five minutes in contrast to one hour by the hand-forging process. Production is thus at least 12 times faster, and the machine does not require a skilled operator to run it. The cost of making heavy dies is thus greatly reduced by the use of our machine.

2

Briefly, our machine comprises a suitable frame, a horizontally extending bed on the frame, a fixed forming tool on the bed, a sliding anvil mounted on a movable ram which moves horizontally in very short reciprocating strokes of great power, means (in this case including an adjustable cam, preferably hydraulically operated), for extending the length of the ram and hence regulating the space between the forming tool and the movable anvil, and the point at which the force is applied to the object, and means for moving the ram horizontally by short reciprocating strokes (which in this embodiment comprises an eccentric mounted on the main operating shaft). In addition, on the same machine and utilizing the same reciprocating ram we provide an auxiliary bending device for bending lighter flat die stock edgewise into an arcuate shape, which includes a separate fixed forming tool and movable anvil. This edge bending of flat die stock is done to provide a tapered or sloping surface vertically for the die stock and to provide enlarged clearance for the cut pieces inside the die and thus prevent clogging of the die when in use.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

- Fig. 1 is a plan view of our machine;
- Fig. 2 is a front end elevation;
- Fig. 3 is a side elevation from the left of Figs. 1 and 2;
- Fig. 4 is a side elevation of the cam mechanism with the cam partially rotated, and partially in section;
- Fig. 5 is a plan view (with a portion in horizontal section, on line 5—5 of Fig. 3) of the auxiliary bending device for bending flat die stock edgewise;
- Fig. 6 is a view similar to Fig. 5 of the auxiliary bending device showing the bending operation;
- Fig. 7 is a vertical section on line 7—7 of Fig. 6;

Fig. 8 is a perspective view of a section of large die stock used in walker dies, and

Fig. 9 is a perspective view of a section of smaller die stock used in making clicker dies.

In the drawings, 10 represents the frame of the machine and includes legs 11 and the horizontal top or bed 12. Rigidly mounted on the frame of the machine is a fixed forming tool 15 and the anvil support includes clamping bracket 16, vertical supports 17, bolts 18 and nut 19. A ram 20 is mounted in the bed 12 of the machine for horizontal, reciprocating movement therein and carries the sliding anvil 22 fixedly mounted on the front end of the ram 20. As seen more particularly in Fig. 1, the forming tool 15 is egg- or pear-shaped in cross section, having a rounded front portion 15a. The sliding anvil 22 in turn is fork-shaped in cross-section having arm portions 22a, which extend around the sides of, and span the rounded central portion 15a of the fixed forming tool.

The means for moving the ram 20 in a horizontal reciprocating movement includes the rocker arm 25 having a cylindrical top portion 26 fitted in a complementary groove in the under portion of the ram 20. At its bottom end rocker arm 25 is mounted for oscillating movement about a horizontal pivot 28 mounted in bracket 29 and suitably bolted to the frame of the machine, as by bolts 30 (Fig. 3). A driving arm 35 is mounted on the frame of the machine for horizontal reciprocating movement beneath the horizontal ram 20 and at its front end carries a bifurcated bracket 36 having fingers 36a which extend around the two sides of rocker arm 25 and carry horizontal shaft 37 passing through rocker arm 25 and on which rocker arm 25 is pivoted for oscillating movement.

The driving shaft 40 is mounted in suitable bearings 42 and carries thereon an eccentric 45, which rotates in the bearing box 46 which forms the rear parts of driving arm 35. The eccentric 45 has an eccentricity of .080 inch, and the main driving shaft 40 is driven by a variable speed device which rotates shaft 40 from 50 to 300 revolutions per minute, and the result is that driving arm 35, ram 20 and sliding anvil 22 are thus given a reciprocating horizontal movement of .080 inch from 50 to 300 times per minute, whereby a rapid series of short blows of great force are imparted to the die stock 24 (as shown in Fig. 3). A coil spring 48, attached to the frame 10 of the machine at one end and to a hook 49 on the rear end of ram 20, serves to keep ram 20 in a retracted position at all times.

Means are also provided for extending the length of driving arm 35 and hence the position of sliding anvil 22 and ram 20 with respect to eccentric 45, for the purpose of regulating the space between the movable anvil 22 and the forming tool 15, and hence the point at which the force is applied to the piece of die stock 24, or other object being bent. This means comprises cam means 50 (shown in Figs. 3 and 4), which includes cam members 50a and 50b having inclined abutting cam surfaces 51a and 51b which are slidably rotated with respect to one another and carry horizontal edge stops 52a and 52b respectively. Cam member 50a is fixedly mounted on shaft 54, in turn mounted in driving arm 35, by means of pin 55. Cam member 50b in turn is rotatably mounted on fixed shaft 54, being fixed to pinion 56 by means of pins 57 and arranged to travel on transverse horizontal rack 58. Rack 58 is caused to traverse the machine horizontally

and transversely by arm 59 fixedly attached thereto at its top end, and which arm 59 is attached at its other end to the rod 61 of a double acting hydraulic cylinder 60 suitably mounted on the frame 10. Flexible connections 62 (Fig. 3) run to a valve and sump 63. As the hydraulic cylinder 60 is a standard device in all respects its construction need not be described in detail. The valve control 63, also of standard construction which may be operated by hand or from a foot treadle, such as 64, controls the action of hydraulic cylinder 60. As will be understood from the construction, the distance between the movable anvil 22 and the forming tool 15, and hence the point at which the bending force is applied to the die stock 24 or other object being shaped, is determined by the regulating valve 63 which through arm 59 moves the rack 58 to the right (as shown in Fig. 2), which rotates the pinion 56 in a counterclockwise direction and hence opens the cam members 50a and 50b, as shown in Fig. 4. This thus extends the length of driving arm 35, and moves forward the starting position of sliding anvil 22 with respect to the forming tool 15.

Means for driving arm 35 in reciprocating horizontal movement is provided, which includes a source of power, such as an electric motor (not shown), which by a sprocket chain (not shown) drives sprocket wheel 41 mounted on the horizontal driving shaft 40. Suitable switches or controls, of course, are provided for regulating the speed of the electric motor which being of standard construction, need not be described in detail.

In operation, it will be understood that the piece of heavy die stock 24 (separately shown in Fig. 8), which is a straight flat strip of steel, has a template or pattern 65 of the desired shoe part shape clamped to it at right angles, as shown more particularly in Fig. 2 by a suitable clamping tool 66. A suitable clamping tool (as shown in Figs. 1 and 2), is that disclosed in Leskiewicz Patent No. 2,446,773, granted August 19, 1948. The strip of die stock 24 is then placed vertically between the forming tool 15 and sliding anvil 22 and a switch or clutch (not shown) is then thrown in to operate the machine. This causes the sliding anvil 22 to reciprocate rapidly in strokes of .080 of an inch in length and from 50 to 300 times per minute, and the arm portions 22a of the sliding anvil 22 thus bend and shape the die stock around the rounded front end 15a of the forming tool 15. The amount of the bending done to the die stock is, of course, determined by the template 65 held adjacent to the die stock 24 by the clamping tool 66, previously referred to. Particularly at the start it is necessary for the sliding anvil to be close to the forming tool and this spacing, as previously stated, is controlled through the regulating valve 63. As each portion of the die stock is bent to the desired shape the stock 24 is advanced through the anvil and given the proper bend until the entire piece is bent as shown in Fig. 1. This operation takes about five minutes in this machine.

On the same machine, and utilizing the same reciprocating ram 20, we provide an additional, auxiliary bending device for bending lighter flat die stock edgewise into an arcuate shape as shown in Figs. 1, 2 and 3 and in more detail in Figs. 5, 6 and 7. The purpose of this auxiliary bending device is to bend a lighter piece of die stock 70 (Fig. 9), from a flat to an arcuate shape edgewise, and thus to provide a tapering clearance in the finished die, which will permit the work pieces to be cleared from the finished

die without clogging. The fixed forming tool 72 includes a pair of abutting members 73 pivoted on vertical pivots 74 and having a transverse horizontal groove 73a therein (Fig. 3). Abutting members 73 are rigidly supported except for pivotal movement on stationary bed 12 by bracket 72a. A moving anvil 75 having overhanging flange 76 is rigidly mounted on the top surface of the reciprocating ram 20 (Fig. 3). The auxiliary bending device is operated by placing a section of die stock 70 (Figs. 9 and 6) flatwise between the forming tool 72 and the movable anvil 75, and causing the reciprocating ram to push the movable anvil 75 and die stock 70 against the abutting members 73. The abutting members 73 yield pivotally as shown in Fig. 6 and a bending force is thus applied to the die stock 70 causing it to bend edgewise into an arcuate shape as shown in Fig. 6.

It will thus be seen that we have provided a power bending machine for forming heavy dies from flat strip, cold rolled steel, with means on the same machine for additionally bending lighter flat die stock edgewise into an arcuate shape. Our machine thus greatly reduces the cost of making such dies.

We claim:

1. In a power bending machine, a frame, a horizontally extending bed on the frame, a forming tool fixed on the bed, a ram movable horizontally within said bed, an anvil mounted on said ram to cooperate with said forming tool, and means for varying the starting position of said anvil with respect to said forming tool, including cam members having abutting inclined surfaces, means including a rack and pinion and a hydraulic cylinder for rotating one cam member relatively to the other on said abutting inclined surfaces, and power means for moving said ram and anvil thereon against said forming tool in short reciprocating strokes, for bending metal stock placed between said anvil and forming tool.

2. In a power bending machine, a frame, a horizontally extending bed on the frame, a forming tool fixed on the bed, a ram movable horizontally within said bed, an anvil mounted on said ram to cooperate with said forming tool, a driving arm mounted beneath said ram, a rocker arm pivotally mounted at its bottom end to a fixed part of the machine and at its top end connecting said driving arm and said ram, a transverse operating shaft, and an eccentric mounted on said shaft, and a source of power for rotating said operating shaft and eccentric mounted thereon for moving said driving arm and anvil thereon against said forming tool in short reciprocating strokes, for bending metal stock placed between said anvil and forming tool.

3. In a power bending machine, a frame, a horizontally extending bed on the frame, a forming tool fixed on the bed, a ram movable horizontally within said bed, an anvil mounted on said ram to cooperate with said forming tool, and means for varying the starting position of said anvil with respect to said forming tool, including cam members having abutting inclined surfaces, and means for rotating one cam member relatively to the other on said abutting inclined surfaces, a driving arm mounted beneath said ram, a rocker arm pivotally mounted on its bottom end to a fixed part of the machine and at its top end connecting said driving arm and said ram, a transverse operating shaft, and an eccentric mounted on said shaft, and a source of power for rotating said operating shaft and

eccentric mounted thereon for moving said driving arm, and hence the ram and anvil thereon against said forming tool in short reciprocating strokes, for bending metal stock placed between said anvil and forming tool.

4. In a power bending machine, a frame, a horizontally extending bed on the frame, a forming tool fixed on the bed, a ram movable horizontally within said bed, an anvil mounted on said ram to cooperate with said forming tool, and means for varying the starting position of said anvil with respect to said forming tool, including cam members having abutting inclined surfaces, means including a rack and pinion and a hydraulic cylinder for rotating one cam member relatively to the other on said abutting inclined surfaces, a driving arm mounted beneath said ram, a rocker arm pivotally mounted on its bottom end to a fixed part of the machine and at its top end connecting said driving arm and said ram, a transverse operating shaft, and an eccentric mounted on said shaft, and a source of power for rotating said operating shaft and eccentric mounted thereon for moving said driving arm, and hence the ram and anvil thereon against said forming tool in short reciprocating strokes, for bending metal stock placed between said anvil and forming tool.

5. In a power bending machine, a frame, a horizontally extending bed on the frame, a forming tool fixed on the bed, a ram movable horizontally within said bed, an anvil mounted on said ram to cooperate with said forming tool, ram actuating means including a driving arm and a rocker arm engaging said ram, means for varying the starting position of said anvil with respect to said forming tool including cam members having abutting inclined surfaces and means for rotating one cam member relatively to the other on said abutting inclined surfaces, a transverse operating shaft, an eccentric mounted on said shaft and a source of power for rotating said operating shaft and eccentric thereon for moving said driving arm and rocker arm and hence the ram and anvil thereon against said forming tool in short reciprocating strokes, for bending metal stock placed between said anvil and forming tool.

6. In a power bending machine, a frame, a horizontally extending bed on the frame, a forming tool fixed on the bed, a ram movable horizontally within said bed, an anvil mounted on said ram to cooperate with said forming tool, means for varying the starting position of said anvil with respect to said forming tool, including cam members having abutting inclined surfaces and means for rotating one cam member relatively to the other on said abutting inclined surfaces, ram actuating means including a driving arm mounted beneath said ram, a rocker arm pivotally mounted at its bottom end to a fixed part of the machine and at its top end connecting said driving arm to said ram, a transverse operating shaft, an eccentric mounted on said shaft, and a source of power for rotating said operating shaft and eccentric mounted thereon for moving said driving arm and hence the ram and anvil thereon against said forming tool in short reciprocating strokes, for bending metal stock placed between said anvil and forming tool.

7. In a power bending machine, a frame, a horizontally extending bed on the frame, a forming tool fixed on the bed, a ram movable horizontally within said bed, an anvil mounted on

said ram to cooperate with said forming tool, means for varying the starting position of said anvil with respect to said forming tool, including cam members having abutting inclined surfaces and means for rotating one cam member relatively to the other on said abutting inclined surfaces including a rack and pinion and a hydraulic cylinder, ram actuating means including a driving arm mounted beneath said ram, a rocker arm pivotally mounted at its bottom end to a fixed part of the machine and at its top end connecting said driving arm to said ram, a transverse operating shaft, an eccentric mounted on said shaft, and a source of power for rotating said operating shaft and eccentric mounted thereon for moving said driving arm and hence the ram and anvil thereon against said forming tool in short reciprocating strokes, for
